[57] CLAIM

The ornamental design for a modular newsstand, as shown and described.

DESCRIPTION

FIG. 1 is a perspective view of a modular newsstand showing my new design, the adjacent modular newsstands being shown in broken lines for illustrative purposes only;

FIG. 2 is a top plan view thereof;

FIG. 3 is a front elevational view thereof;

FIG. 4 is a side elevational view taken from the right of FIG. 3, the side opposite being a mirror image thereof;

FIG. 5 is a rear elevational view thereof; and

FIG. 6 is a front elevational view with the cover in place.

FIG. 1

FIG. 2

FIG. 3

FIG. 4
